LACING MACHINE
Leo Rosen, 9414 St. Andrews Way, Silver Spring, Md.
Filed June 19, 1962, Ser. No. 203,651
7 Claims. (Cl. 289—18)

This invention is in lacing machines, and more particularly is intended as an apparatus for lacing or securing together into a tight bundle or cable a number of electric wires by means of a continuous cord. This sort of cabling is common in electronic and electrical construction. Customarily, it consists of tying a knot about a bundle of wires, extending one end of the cord a desired distance along the bundle, tying a second knot, and so on to approximately the ends of the wires; and ordinarily the procedure is accomplished by hand, and requires considerable dexterity and strength.

While my invention will be described particularly in connection with cabling, as mentioned, its applicability to other arts, as sail making, lawn furniture manufacture of certain kinds, etc., will become apparent.

The principal object of the invention is to provide a machine for lacing or tying together two or more objects.

It is also an object of the invention to provide means for tying together by means of a continuous cord two or more elongated objects into a single elongated package or bundle.

Additional objects of the invention will become apparent from a reading of the following specification and claims.

In the drawings:

FIGURE 1 is a sectional view of a novel needle used in my machine.

FIGURES 2a and 2b, 3a and 3b, 4a and 4b, 5a and 5b, and 6a and 6b are side and front views (in pairs) of the principal elements of my lacing machine in successive stages of operation.

FIGURE 7 illustrates one form of knot which may be tied during operation of my machine.

In the description to follow, manual adjustment of the parts and manual operation thereof will be assumed. It is within the spirit of the invention, however, to provide suitable supports for the parts, and to supply power from a desired source, with levers, cams, and the like, to direct and control the necessary motions.

Considering now the drawings in detail, and especially FIGURE 1, 10 is a gapped circular needle, hollow substantially throughout its length, except as hereinafter mentioned, the needle being shown in section. Drive rollers 11, 12, 13, and 14, supported in any convenient manner, hold and guide the needle, and, it should be understood, may be furnished with power (no source being shown) to rotate the needle as will be herein-after explained.

One end of the needle, 16, preferably is pointed, and the shape of the other end, 17, is essentially immaterial.

Interiorly of the needle adjacent end 16 thereof is arranged a bobbin 20 which serves as a source of supply for the cord or twine 21 which is employed in lacing and tying. Just counterclockwise of bobbin 20, and arranged to slide within needle 10, is a feed device 22 of known type embodying jaws for gripping cord 21 with a prearranged degree of tightness, that is, to provide a predetermined amount of drag; this action will be further explained.

Also within needle 10, extending from device 22 to a terminal closure 23, is a helical spring 26. This spring may be preloaded or not as circumstances indicate. Closure 23 is shown as threaded into the needle, at 27, and is provided with an opening 28 through which cord 21 may move freely.

2

The construction produces an action or mode of operation as follows: with the parts in approximately the relations as shown in FIGURE 1, cord 21 may be pulled from end 17 of needle 10, through orifice 28 in closure 23, and will, at first, pull feed device or clutch 22 along with it, thereby compressing spring 26 between the clutch and closure 23; a point will be reached, however, at which the pressure of spring 26 will counterbalance the drag inherent in clutch 22, and at this point clutch 22 will become stationary, and the cord, if pulled, will be pulled therethrough; at any point, after spring 26 has been compressed, release of cord 21 will permit the spring to force clutch 22 back to its initial position, with an amount of cord equal to the motion of device 22 being withdrawn into the needle.

In FIGURES 2a through 6b may be seen a fragment of a base structure 50 with a hook 51 extending from the top thereof under which extends a bundle of wires 52 in the process of being laced or tied together. Just below the top of the base may be seen two further extending hooks 53 and 54, and these are to be understood to be rotatable about their individual longitudinal axes.

Cord 21 may be seen to be extending from a knot 60 into needle 10 through closure 23 (first passing beneath hook 51), and should be assumed to be threaded through the needle and attached to bobbin 20 as shown in FIGURE 1.

If, under the conditions of FIGURES 2a and 2b, the needle is caused to make one clockwise rotation about its virtual axis A, cord 21 will be looped about hooks or fingers 53 and 54, and the various parts will be found to be in the conditions and relations shown in FIGURES 3a and 3b.

Following this first rotation, needle 10 is moved to the right in its own plane, so that its imaginary axis reaches point B, and its inclination is changed from that shown in FIGURES 2a and 3a to that shown in FIGURE 4a, and caused to make a second clockwise rotation, passing beneath cord 21, between fingers 53 and 54, to the right of cable 52, and over the cord in the area between the cable and finger 54. Spring 26, inside the needle, has been compressed during the operations described.

When the needle returns to its initial angular position (see FIGURES 6a and 6b), fingers or hooks 53 and 54 are rotated toward each other (see especially FIGURE 6b), cord 21 slips from them, and, under the urging of spring 26, a knot 60' is pulled tight about cable 52, hooks 53 and 54 are returned to their initial positions, needle 10 is shifted back to axis A, and the operator moves the cable to the next desired knot position. Obviously, this last step, also, may be mechanized.

The lacing or tying operation has been described as a sequence of separate steps, but it is possible for some of the steps to overlap each other, nor is it necessary to stop the needle after its first rotation.

Furthermore, certain variations are possible; for example, additional strength may be provided by repeating the wrapping operation (FIGURES 2 and 3) before proceeding to tie (FIGURES 4a through 6b).

The knot formed by the mechanism operated as described is shown in FIGURE 7. It will be seen to be self-locking in nature, that is, once drawn tight, it will not release if the cord is accidentally severed.

The foregoing description is in specific terms, and many modifications will suggest themselves. For the true scope of the invention, therefore, reference should be had to the appended claims.

I claim:

1. A device of the character described including a substantially circular needle, a cord feeding mechanism car-

ried thereby, means for turning said needle through one rotational path to form a loop of said cord, said further means turning said needle through another rotational path for completing a knot of said cord.

2. A device according to claim 1, further characterized by spring means carried by said needle having a normal relatively untensioned condition, tensioned responsive to operation of said cord feeding mechanism and to the rotation of said needle and operative thereafter to cause said cord feeding mechanism to pull tight a completed knot.

3. A device of the character described comprising a substantially circular needle and means for turning the same in a plurality of rotational paths, a cord supply, a spring, means for feeding cord from said supply during rotation of said needle, means for tensioning said spring as said cord is fed, a support, means mounted adjacent said support for holding an article to be wrapped, means mounted adjacent said holding means for retaining a loop of cord during a wrapping operation and subsequently for releasing the same.

4. A device of the character described comprising a substantially circular hollow needle having an initial plane and an initial axis of rotation and including a cord supply, a spring, and a feeding device for holding cord from said supply, for releasing said cord responsive to predetermined tension thereon, and for compressing said spring as cord is pulled from said supply, a support, means mounted adjacent said support for holding an article to be wrapped, other means mounted adjacent said holding means for holding a cord and means for turning said needle through substantially one rotation thereby to wrap cord pulled from said supply in a loop about said other means and the article to be wrapped, said needle being tilttable from its initial plane for shifting its axis of rotation, said turning means turning the same through substantially another rotation to directly wrap the cord over one portion of said loop and under another portion thereof to form a knot, said other means being turnable to release said cord therefrom.

5. A device of the character described comprising a substantially circular needle, a cord supply, means for turning said needle through a first rotational path to cast a loop of cord from said supply about an article to be wrapped, said turning means turning said needle through a second rotational path to feed cord from said supply over one portion of said loop and under another portion thereof to form a knot, and spring means for pulling said knot tight.

6. A device of the character described comprising a substantially circular hollow needle having an initial plane and an initial axis of rotation and including a cord supply, a spring having an initial condition and a feeding device mounted for movement within said needle and operable to hold cord from said supply, to compress said spring as said cord is pulled from said needle, and to

release said cord in response to predetermined tension thereon, a support, means for holding an article to be wrapped and tied adjacent said support, two fingers each having a cord holding position and a cord releasing position, means for turning said needle through substantially one revolution to wrap cord pulled from said supply about said fingers and an article to be wrapped, said fingers being in their said cord holding positions, said needle being tilttable from its initial plane and shifting its axis of rotation and said turning means turning the same through substantially a second revolution to feed cord from said supply under the cord stretched between said two fingers during the first revolution of said needle and over the cord stretched between the article and one of said fingers during the first revolution of said needle, said cord holder fingers being turnable to release said cord from said fingers.

7. A device of the character described comprising a substantially circular hollow needle having an initial plane and an initial axis of rotation and including a cord supply, a spring and a feeding device mounted for movement within said needle and operable to hold cord from said supply, to compress said spring as said cord is pulled from said supply, and to release said cord in response to predetermined tension thereon, a support, means for holding an article to be wrapped and tied adjacent said support, two fingers for holding said cord, means for turning said needle through substantially one revolution to wrap cord pulled from said supply about said fingers and an article to be wrapped, said needle being tilttable from its initial plane and shifting its axis of rotation and said turning means turning the same through substantially a second revolution to feed cord from said supply under the cord stretched between said two fingers during the first revolution of said needle and over the cord stretched between the article and one of said fingers during the first revolution of said needle, said cord holder fingers being turnable to release said cord from said fingers thereby to release tension on said spring to permit the same to pull said cord tight about the article.
